UNITED STATES PATENT OFFICE

152,436

DESIGN FOR A DRAPEABLE UMBRELLA

Emanuel Schreck, Forest Hills, N. Y.

Application June 25, 1947, Serial No. 139,902

Term of patent 14 years

(Cl. D88—3)

To all whom it may concern:

Be it known that I, Emanuel Schreck, a citizen of the United States of America, and residing in the Borough of Forest Hills, city of New York, county of Queens, and State of New York, have invented a new, original, and ornamental Design for a Drapeable Umbrella, of which the following is a specification, reference being made to the accompanying drawing, forming part thereof.

Fig. 1 is a side-elevational view of a drapeable umbrella in closed condition and showing my new design;

Fig. 2 is a top plan view, partly in section on line 2—2, of the drapeable umbrella seen in Fig. 1;

The essential features of my design reside in the portion shown in full lines.

I claim:

The ornamental design for a drapeable umbrella, substantially as shown and described.

EMANUEL SCHRECK.
